UNITED STATES PATENT OFFICE

OSKAR FISCHER, OF BERLIN, GERMANY

COPYHOLDER FOR TYPEWRITERS

Application filed September 24, 1927, Serial No. 221,798, and in Germany December 23, 1925.

This invention relates to a copy-holder for typewriting machines and consists essentially in connecting the copy-supporting plate adjustably to a curved supporting arm composed of parallel, channelled, inter-connected members, said arm being pivotally connected to a base so as to allow the plate to be normally maintained in a convenient position above the typewriting machine and turned back when not in use.

Being composed of channelled members, the supporting arm can be made light and yet very steady, which is essential for a good copy-holder.

15 It should be observed that pivotally-arranged copy-holders are known per se.

Fig. 1 of the accompanying drawings represents a side view of the improved copy-holder,

20 Fig. 2 is a cross-section on the line 2—2 of Fig. 1,

Fig. 3 is a rear view of the copy-holder,

Fig. 4 is a front view of a copy-holder provided with two supporting arms,

25 Fig. 5 is a side view of the same,

Fig. 6 is a horizontal section on the line 6—6 of Fig. 4,

Fig. 7 is a view of the copy-supporting plate seen from the lower edge of the same,

30 Fig. 8 is a front view of the lower part of the plate,

Fig. 9 is a view at right angles to Fig. 8,

Fig. 10 is a view showing a modification of the supporting arm,

35 Fig. 11 is a view at right angles to Fig. 10,

Fig. 12 is a cross-section on the line 12—12 of Fig. 11, and

Fig. 13 is a cross-section on the line 13—13, of Fig. 11.

40 The copy-holder consists of a copy-supporting plate 9 and a curved supporting arm or bracket 4 which latter holds the plate in a suitably-inclined position. The bracket is attached to the typewriter table so that it can hold the plate 9 over the platen of the machine, right in front of the operator. Thus the copy as well as the machine can be readily watched at the same time. The bracket 4 is held by a pivot pin 3 on a screw clamp 1 or 45 the like whereby the copy-holder is connected

to the top of the typewriter table. The arrangement is such that the bracket can be adjusted for bringing the plate more or less to the front and also for turning it right back so as to give free access to the machine for 55 the insertion and removal of the paper or for other operations. This latter feature is known per se.

According to the invention the supporting arm or bracket 4 of the copy-holder is composed of two parallel members 4a and 4b which are inter-connected and distanced by stays 28, 29 and 30. The members are made of metal plate and channelled, as shown in Fig. 2, to give the necessary strength and 60 rigidity. A web 31 connects the two members at one end and carries the copy-supporting plate 9. The latter is fitted with two parallel rails 32 and 33 between which the web 31 is slidably guided so that the plate can be adjusted to different positions and also entirely removed from the bracket. The guide rails are composed of metal strips which are formed along the inner sides with offset portions under which the web 31 engages. The 65 metal strips forming the guide rails 32 and 33 are also extended and beaded so as to form sleeves in which the ends of a wire shackle 34 are telescopically guided. The shackle 34 serves, when extended, as a support for large 70 copy sheets, and it carries a clip 35 to which the sheets may be connected.

The pivot pin 3 of the bracket is secured by means of a grub screw 36 to a lug 2a on the clamp 1. The bracket members are situated at opposite sides of the lug, and to obtain a steady and yet easy joint without careful fitting, resilient washers 37 are introduced between the lug and the bracket members. The pivotal deflection of the bracket is limited by the lowermost stay 30 which is located in a recess in the lug 2a and stops the bracket by abutment against the lug portions at opposite sides of the recess. Further limitation of the deflection in either direction is effected by two screw abutments 38 and 39 which are fitted in the lug 2a so that they can be screwed up against the stay 30. To retain the screws in adjusted position, they are braked by springs 40 and 41 which abut 75 80 85 90 95

against the lug 2a and against the screw head. The plate 9 may be fitted with a line indicator 21.

In cases where a particularly steady copy-holder is required, the construction shown in Figs. 4-9 may be resorted to. In this construction the bracket is composed of two parallel members 4c and 4d which are held by stays 46, 47 and 48 at a considerable distance apart, each member being pivoted to a separate lug 2b mounted on a base plate 49 whereby the holder is secured to the top of the type-writer table. Each member is composed of two channelled metal strips which in this case are joined together as best shown in Figs. 12 and 13 so as to form a square tube having rounded corners. The tubes are forked for engagement with the lugs 2b, and springs 37 are introduced between the forks and the lugs so as to obviate careful fitting. The upper stay 46 consists in a plate having a centrally-disposed guide strip 50 the edges of which are offset for engagement with the beaded edges of the corresponding guide strip 51 connected to the back of the copy-supporting plate 9. An eccentric disc operated by a hand lever 52, is fitted at the back of the stay 46 for clamping the plate 9 to the stay in different positions of adjustment. The lower edge 53 of the plate 9, which is upturned for supporting the copy, is strengthened by two angle pieces 54 and by an additional strip 55 between which and the parts 53 slots 56 are formed for the reception of the supporting arms of a lamp fitting 25. The strip 55 is slit at 57 so as to form resilient tongues for engagement with the lamp-supporting arms.

The stay 48 co-operates with a stop 58 for limiting the movement of the holder about the pivots 3. A screw 59, which is braked by a spring 60, is fitted at one side of the stop for regulating the normal position of the holder.

The tubular form of bracket may also be employed where only one arm is used, as shown in Figs. 10 and 11. The metal channels may be stamped with clips 15 for the support of the lamp wire. The arm is forked at both ends and flanged at the upper end for the reception of a plate 50' for engagement with the guide strip 51 of the copy-supporting plate.

I claim:

1. A copy-holder, comprising a copy-supporting frame, a curved supporting arm for said frame composed of two channelled and inter-connected members disposed with their channelled faces opposing each other and formed at their top ends with enlargements providing a plane face, a guide member secured to said plane face and having said copy-supporting frame slidably mounted thereon, and a base to which the arm is connected.

2. A copy-holder, comprising a copy-sup-

porting frame, a curved supporting arm for said plate composed of two channelled and inter-connected members disposed with their channelled faces opposing each other, a base to which said arm is pivotally connected, and adjustable abutments for regulating the deflecting movements of said arm.

3. A copy-holder, comprising a copy-supporting frame, a curved supporting arm for said frame composed of two channelled and inter-connected members disposed with their channelled faces opposing each other, a base, a lug on said base engaging the members at the end of said arm, a pivot pin passed through said lug and through the said two members, a stay connecting the said members, and screws connected to said lug in position for cooperating with said stay for limiting the deflecting movements of the arm.

4. A copy-holder, comprising a supporting arm, a base on which said arm is pivotally mounted, a copy-supporting frame, guide strips mounted respectively on said copy-supporting frame and on the free end of said arm, said guide strips engaging each other for holding the frame on the arm in different positions, and a clamping member adapted to secure said frame on said arm in different positions of adjustment.

5. A copy-holder, comprising a copy-supporting frame, a curved supporting arm for said frame composed of two channelled and inter-connected members disposed with their channelled faces opposing each other, a base, a lug on said base engaging between the members at the end of said arm, a pivot pin passed through said lug and through the said members, guide strips mounted respectively on said copy-supporting frame and on the free end of said supporting arm, said guide strips engaging each other for holding the plate on the arm in different positions, and a clamping member mounted on said arm so as to bear against said frame for securing the same in different positions of adjustment.

6. A copy-holder, comprising a copy-supporting frame, a curved supporting arm for said frame composed of two channelled and inter-connected members disposed with their channelled faces opposing each other and constructed at their top ends for having said frame directly mounted thereon, a base provided with a lug engaging between the bottom end of said members, a pivot bolt for jointing said members and lug, and resilient washers between said members and lug for steadyng the movement of said arm.

7. A copy-holder, comprising a copy-supporting frame, a curved supporting arm for said frame composed of two channelled and inter-connected members disposed with their channelled faces opposing each other and constructed at their top ends for having said frame directly mounted thereon, a base provided with a lug engaging between the bottom

ends of said members, a pivot bolt for jointing said members and lug, and resilient washers placed between said lugs and the end faces of the flanges of said members.

8. A copy-holder, comprising a copy-supporting frame, a curved supporting arm for said frame composed of two channelled and inter-connected members disposed with their channelled faces opposing each other and constructed at their top ends for having said frame directly mounted thereon, a base provided with a lug engaging between the bottom ends of said members, a pivot bolt for jointing said members and lug, guide strips on the copy-supporting plate and on the free end of the supporting arm, said guide strips being adapted to inter-engage for holding the plate on the arms in different positions, and the strips on the plate being beaded so as to form tubular guides and a shackle arranged to telescope in said tubular guides so as to form an adjustable extension of the copy-supporting frame.
